METHOD OF AND MACHINE FOR
MANUFACTURING SHOESAnthony Labrie, Haverhill, Mass., assignor to
United Shoe Machinery Corporation, Paterson,
N. J., a corporation of New JerseyOriginal application December 31, 1935, Serial
No. 56,966. Divided and this application De-
cember 14, 1937, Serial No. 179,681

15 Claims.

(Cl. 12—6)

The present invention relates to a machine for, and a method of, assembling and sewing shoes of the McKay type, in which type of shoe the stitches of the seam holding the shoe together pass through the outsole, upper and insole of the shoe and appear on the outer surface of the outsole and at the inside of the shoe. In accordance with its general objects, the invention provides a novel method of manufacturing, in a simplified and improved manner, shoes of the McKay or other similar types, and a new and improved machine well adapted for use in performing the several steps of the method. The invention is hereinafter illustrated and described as embodied in a machine similar to that disclosed in inventor's co-pending application for U. S. patent Serial No. 56,966, filed December 31, 1935, of which the present application is a division.

In the manufacture of a McKay shoe according to usual shoe making practice, the insole is secured to a suitable solid wooden last by tacks. The upper is then applied to the last and molded into close fitting relation therewith so that the marginal edges of the upper overlap the edges of the insole. Additional tacks are driven through the overlapping portions of the insole and upper against a metal plate on the bottom of the last to clench the tacks in position, thus temporarily fastening the upper to the insole. The temporarily fastened upper and insole are then removed from the last. After removal from the last, the shoe is sewed on a so-called McKay stitcher having a rotary horn designed to extend within the shoe and to cooperate with a straight reciprocating hook needle in securing an outsole to the temporarily fastened upper and insole, the stitches passing through the edges of all the parts. Thereafter, the marginal edges of the outsole are trimmed, and the heel is attached.

This method of manufacture has the objectionable feature that the removal of the last, while the insole and upper are held together by the temporary fasteners only, often strains or tears loose these fasteners so that difficulty is encountered in holding the shoe parts together properly for the sewing operation. Also for the best results this method necessitates the re-insertion of the last into the shoe after the sewing operation, so as to adequately support the shoe parts during the sole trimming, heel attaching and other finishing operations.

An object of the present invention is to provide a method of manufacturing shoes which will be free from the defects above mentioned and, with this object in view, the method of the present

invention contemplates assembling the parts of the shoe on a last and, while the parts are supported on the last, working the upper into lasted position and, without removing the last, securing the outsole and upper permanently together by a through-and-through seam, the stitches of which appear upon the inside of the shoe and upon the outer surface of the outsole.

A feature of the invention contemplates temporarily holding the upper in lasted position during the sewing operation and preferably a series of sticker points are employed for this purpose, which sticker points are mounted in the last and are projected through the upper and through the insole, when the shoe is provided with an insole, after the upper has been worked into lasted position and are withdrawn from the shoe parts after the sewing operation or before the final finishing of the shoe so as to permit the shoe to be removed from the last.

The new and improved machine which embodies various features of the present invention comprises a last upon which the upper, the insole, when the shoe is provided with an insole, and the outsole may be assembled, and lasting and sewing mechanisms associated with the last by which the upper may be first worked into lasted position and then the outsole, after being placed on the lasted upper, may be permanently secured to the shoe by a through-and-through seam, the stitches of which appear at the inside of the shoe and upon the outer surface of the outsole.

Broadly considered, the invention contemplates the provision of any suitable forms of lasting and sewing mechanisms adapted to cooperate with the last in working the upper into lasted position and in forming the through-and-through seam. For convenience of operation, and for the attainment of uniform results, as well as to provide a simple and efficient machine, the lasting mechanism preferably consists of bed lasting units operating from the heel and toe ends of the shoe to grip and wipe the upper over the surface of the supporting last. Also, to provide a simple and compact machine by which the through-and-through seam may be formed while the upper and outsole are supported on the last, the invention contemplates mounting the sewing mechanism and last in such a manner that the mechanism and last are relatively movable towards and from operative position and are also rotatably movable to transfer the point of operation of the sewing devices around the shoe.

In order to permit the stitches of the seam to pass through the outsole and upper and appear

55

on the inside of the shoe, the invention contemplates the provision of a hollow last, and certain features of the invention are embodied in the series of upper holding points, together with 5 the means whereby these points may be projected through the insole and upper and are arranged to hold the upper in place after being worked into lasted position by the upper clamping and wiping devices.

- 10 In addition to the features above referred to, the machine hereinafter described as embodying the several features of the invention comprises many other novel constructions and arrangements of parts hereinafter described and claimed, the 15 advantages of which will be obvious to those skilled in the art from the following description, taken in connection with the accompanying drawings in which is illustrated the preferred form of machine which may be utilized in practising 20 the method of the present invention.

Referring to the drawings Fig. 1 is a view in front elevation of the machine of the invention showing an already lasted shoe being sewed to permanently secure the parts thereof together; 25 Fig. 2 is a view in side elevation of the machine, looking from the right, certain parts of the lasting units having been omitted; Fig. 3 is a sectional view on an enlarged scale taken along the line 3—3 of Fig. 2; Fig. 4 is a view in front elevation, partly broken away, and shown in section, of a portion of the machine, illustrating the relative positions of the shoe and sewing mechanism during sewing operations; Fig. 5 is a plan view of a support and form for guiding 30 the sewing mechanism about the shoe; Fig. 6 is a view in side elevation of a shoe, as constructed on the machine, embodying the present invention; Fig. 7 is a sectional view, showing the inside of the shoe, as viewed along the line 7—7 35 of Fig. 6; Fig. 8 is a sectional view of the shoe shown in Fig. 6, taken along the line 8—8; and Fig. 9 is a view of a bottom portion of the shoe, looking at the tread surface of the outsole.

Referring to Figures 1 and 2 of the drawings, 40 the illustrated machine comprises a base constructed of four upright angle section legs 2 connected at their upper ends to a horizontal flanged metal top 4 and intermediate their ends by a partition 5 similar in shape to the top. To 45 support the parts of the shoe to be operated upon, a hollow metal last 6 is removably mounted upon the top 4 of the base. In the manufacture of a shoe, an insole is first applied to the bottom of the last and tacks are driven therethrough 50 into wooden plugs 8 (Fig. 3) inserted into the last bottom to receive them. If a metal shank 55 stiffener is to be used, it is perforated to receive one of the tacks which secures the insole to the last. The upper is then placed over the last in 60 position to be acted upon by the lasting devices.

At the toe and heel ends of the last are lasting units mounted on the machine to work an upper over the last and cause it to conform properly with the curved surfaces of the last, the 65 margin of the upper overlapping the edges of the insole. The lasting units are supported on the machine base by sliding carriages 10 mounted on horizontal guideways 11 along which they are movable towards and from the last. The operating devices of each lasting unit are similar 70 to those illustrated and described in U. S. Patents No. 1,495,169 of May 27, 1924, and No. 1,284,870 of November 12, 1918 and constructed in the manner disclosed more clearly in inventor's co-pending application referred to in which there

is an upper embracing and clamping band comprising a supporting chain 12 backed by a soft flexible facing and a pair of oppositely moving wiper plates 14. Each upper clamping band is advanced and closed about one end of the shoe by manipulating a hand lever 16 extending towards the front of the machine. After the clamping band has been forced against the shoe, the wiper plates 14 are moved inwardly towards each other to gather the margin of the upper over the bottom of the last and to iron down the pleats thus formed in the upper margin, in the manner set forth in inventor's application.

To move the carriage 10 of the lasting units towards and from the last and hold them in place on the slides during lasting operations, a hand wheel 18 is provided on each carriage for rotating a spur gear 20 engaging a rack in the guideway and a spring pressed locking plunger 22 is slidably mounted in each carriage to engage an opening 24 in the guideway when the carriage is moved to operative position. This mechanism is substantially the same as that illustrated and described in U. S. Patent No. 1,018,477 granted February 27, 1912.

In the embodiment of the present invention, after the lasting units have been operated, the locking plungers being withdrawn, the units are moved away from the shoe on the last, and a sewing mechanism, also mounted on the machine, is swung into operative relation with the last to secure the shoe parts together with a permanent seam passing through the parts and appearing at the tread surface and within the shoe. While the lasting units are being moved away and the sewing mechanism is being swung into operative relation with the shoe, the parts are held temporarily in position by a series of sticker points, to be described more fully hereinafter.

As more clearly illustrated in Figures 6 to 9, 40 the shoe consists of an upper 26, an insole 28, and an outsole 30 although it is within the scope of the invention to construct a shoe in the same general manner, but omitting the insole 28. The upper 26 is formed over the last 6 in the manner described. After the lasting operations are completed, and the tacks removed, the space between the inturned edges of the upper may be filled by a suitable plastic or other material 32. The outsole 30 is then positioned in proper relation to be attached, and the sewing mechanism 45 is operated to form a chainstitch seam 34, the chain of which appears in a preformed groove at the outer surface of the outsole.

To clamp the outsole to the shoe during the 55 sewing operation a form or clamping plate 36 (see Figs. 4 and 5) is provided, shaped to correspond with the bottom curvature of the shoe and having a soft sponge rubber pad 38 on its lower side to prevent injury to the finished surface of the 60 outsole. The form 36 is mounted on a vertical rod 40 having a triangular shaped reinforcing brace 42 extending lengthwise of the form. The upper end of the rod 40 is fixed to the forward end of a horizontally extending arm 44 (Figs. 1 and 65 2) secured at its rearward end to a vertical shaft 46 mounted loosely in bearings 48 and 50 connected with the rear legs of the machine base.

The sewing mechanism, similar to that described in inventor's application, is carried in a 70 frame consisting of a vertical plate 52 having a right angle flange portion 54 at its forward end. The frame is mounted on a continuous curved track support 56 mounted on vertical pins 58 (see Figs. 1 and 2) extending upwardly from an 75

open ended arm 60, also secured to the vertical shaft 46 which supports the form 36. The end of arm 60 is shaped to surround the last when the arm is lowered over it, so that the curved track and the edges of the form 36 will be spaced to provide a slot through which the sewing mechanism may operate on the shoe.

To permit the sewing mechanism and the form to be moved together towards and from the last, means are provided for raising the shaft 46 so that the arm 60 and support 56 will clear the last. The lower end of the shaft is rotatably connected to a block 62 (see Fig. 2) which is pivotally connected to the upper ends of a pair of links 64. The lower ends of links 64 are connected to an arm 66 secured to a horizontal rock shaft 68 rotatable in suitable bearings on the rearward legs 2. At the right end of rock shaft 68 is fixed a forwardly extending treadle 70 which, when depressed, acts to raise the sewing mechanism and form 36 through the connections thus described.

To hold the sewing mechanism and form in raised position, the shaft 46 carries a collar 71 (see Fig. 2) engaged by a vertically elongated latch plate 72 operated yieldingly against the collar. To retract the latch plate from the collar a hand lever 73 connected to the latch plate is pulled forwardly, the latch plate being withdrawn from beneath the collar 71, so that the sewing mechanism and form 36 may move downwardly against the shoe by gravity. To force the form to a still lower position against the outsole of a shoe so that the outsole may be forced into closer fitting relation with the lasted upper and insole, the rock shaft 68 carries at its left end an arm 74 connected to the rearward end of a treadle lever 76 pivotally mounted intermediate its ends on the left forward leg 2 of the machine. Downward pressure on the forward end of treadle lever 76 is thus transmitted through the rock shaft 68 and to the form.

The support 56, as best shown in Figs. 4 and 5, has three rounded rail or track portions, one at the top, one at the side, and one beneath the support, along which correspondingly shaped truck wheels 78, 80, and 82 on the sewing mechanism ride. In the rearward end of the sewing frame is pivotally supported a vertical carrier 84 for a reciprocating needle bar 86 to the lower end of which is fixed a straight hook needle 88, the needle bar carrier being so located that the needle will pass through the space between the form 36 and the track 56. During the travelling movement of the sewing frame, the needle bar carrier is moved forwardly and rearwardly transversely to the line of feed by the engagement of a finger 90 with the edge of the sole clamping form 36, as more particularly explained in inventor's application above referred to.

In order to advance the sewing mechanism along the support 56 with a sewing movement between the reciprocations of the needle, a shaft in the sewing frame carries a spur gear 92 which engages rack teeth 94 (see Figs. 4 and 5) formed at the inner edge of the support 56. The gear 92 is connected to an intermittent Geneva movement, as described in the application referred to so that the sewing mechanism is moved a stitch length between stitches.

Means is provided within the last 6 for looping the needle during each work penetrating stroke. Within an opening in the bottom of the last 6 a separate sole plate 96 is located (see Figs. 3, 4 and 5) somewhat smaller than the bottom of the last to provide a slot 98 between the last and

plate 96. Within the slot between the last 6 and sole plate 96 a looper 100 is arranged to slide inside the last and to follow the movements of the sewing frame on the support 56 about the last, as more fully set forth in inventor's application. The plate 96 is secured to a similarly shaped supporting plate 102 carried by a double armed bracket 104 fixed to the upper end of a hollow support post 106 (Fig. 3), the lower end of which is flanged and made fast to the partition 5 10 of the machine base. The hollow support post 106 is of sufficient length and so located that the sole plate 96 will lie flush with the edges of the last and also be equally spaced from the sides of the last. The marginal edges of the form 15 plate 36 which guide the transverse movement of the needle bar carrier 84 are shaped to direct the needle in a path corresponding to that of the looper in the slot 98 between needle strokes.

The insole 28 and the outsole 30 of the shoe are 20 perforated under their heel seat portions to provide openings for a shaft 108 carried by the form 36, and when the sewing mechanism and form are swung into operative relation with the last, the shaft 108 passes through the perforations provided and readily fits within the opening of a part carried by the sole plate of the last. The shaft 108 in this relation acts as a means for properly locating the parts of the shoe and form on the last during assembly. To assist further in 30 positioning the form 36 on the last in the proper relation, the vertical shaft 46 which supports the sewing mechanism and form carries a block 110 (Fig. 2) having downwardly extending tongues adapted to enter a slot 112 in the upper surface 35 of bearing 48. The block 110 is so located that when the tongues thereon coincide with the slot 112, the shaft 108 will be in position to enter the opening in the sole plate. Before applying the outsole to a shoe, the outsole cut to the proper 40 size and properly grooved is slipped within the track 56 beneath form 36 where it is held by springs 114 fastened inside the support at suitably spaced points so as to be brought into proper registry with the shoe bottom when the form 36 45 and the sewing mechanism are swung into operating position.

To fasten the insole and upper of a shoe temporarily after the lasting units have operated, a series of sticker points are provided to operate 50 from within the last, as indicated at 116 (Fig. 3). The sticker points are secured to a sticker point operating plate 118 and pass through aligned openings in the sole plate 96 and support plate 102. The sticker points are of a diameter to 55 fit the holes in the sole and support plates, respectively, and their upper ends are reduced in diameter and sharpened to facilitate penetration of the shoe parts. Vertical movement of the sticker point operating plate 118 causes the 60 sticker points to be reciprocated into and from the insole and upper. The sticker points are so located and are of such length that they will pass through the insole and upper just inside the seam line when the plate 118 is raised against 65 the supporting plate 102. When the outsole is pressed down against the upper edges, by the form plate 36, the points will pierce the lower surface of the outsole, but will not pass through the outer or tread surface thereof.

To reciprocate the sticker points, the sticker point supporting plate 118 is connected to the upper end of a rod 120 (Fig. 3) passing loosely through the hollow post 106 and having a connection at its lower end with the central part 75

of a sticker lowering foot operated lever 122 fulcrumed at its rearward end in the base of the machine. To raise the sticker points and force them through the insole and upper of a shoe, a sticker raising foot lever 124 (Fig. 1) is connected at its rearward end with the lower end of rod 120 and is fulcrumed between its ends on the machine frame.

After the sewing operations are finished, the heel of the shoe may be attached, the edges trimmed and other finishing operations performed while the shoe remains supported on the last. Upon removing the shoe the stitches passing through all of the shoe parts will provide ample strength to hold the shoe against distortion as a result of the force required in removing it from the last.

Having thus explained the nature and object of the invention, and having specifically described a machine embodying the invention in its preferred form, what is claimed is:

1. A method of making shoes which comprises assembling an upper and an insole on a last, lasting the upper over the insole, placing an outsole on the lasted upper and insole, and securing the insole, upper, and outsole permanently together while on the last by a thread seam, the stitches of which pass through the parts and appear at the outer surface of the outsole and the inner surface of the insole.

2. A method of making shoes which comprises assembling an upper and an insole on a last, lasting the upper over the insole, temporarily fastening the overlapping edges of the upper and insole together by means passing through the insole and upper from within the shoe, placing an outsole on the lasted upper and insole, securing the insole, upper and outsole permanently together by a thread seam, the stitches of which pass through the parts and appear at the outer surface of the outsole and inner surface of the insole, and thereafter removing the shoe from the last.

3. A method of making shoes which comprises assembling an upper and an insole on a last, lasting the upper over the insole, temporarily fastening the overlapping edges of the upper and insole together by means passing through the insole and upper from within the shoe, placing an outsole on the lasted upper and insole, securing the insole, upper and outsole permanently together by a thread seam, the stitches of which pass through the parts and appear at the outer surface of the outsole and inner surface of the insole, withdrawing the temporary fastening means and thereafter removing the shoe from the last.

4. A method of making shoes which comprises assembling an upper and an insole on a last, lasting the upper over the insole, projecting sticker points from within the last through the overlapping edges of the upper and insole, placing an outsole on the lasted upper and insole, securing the insole, upper and outsole permanently together by a thread seam, the stitches of which pass through the parts and appear at the outer surface of the outsole and inner surface of the insole, drawing into the last the sticker points from the insole and upper, and thereafter removing the shoe from the last.

5. A method of making shoes which comprises assembling an upper and an insole on a last, lasting separately the heel and toe ends of the upper over the insole, projecting sticker points from within the last through the overlapping

edges of the upper and insole after the ends of the upper are lasted, placing an outsole on the lasted upper and insole and securing the insole, upper and outsole permanently together by a thread seam, the stitches of which pass through the parts and appear at the outer surface of the outsole and thereafter withdrawing the sticker points to permit removing the shoe from the last.

6. A method of making shoes which comprises applying an upper to a last, working the upper into lasted relation to the last, placing an outsole on the lasted upper and securing the outsole and upper permanently together while on the last by a thread seam, the stitches of which pass through the parts and appear at the outer surface of the outsole and the inside of the shoe.

7. A method of making shoes which comprises applying an upper to a last, working the upper into lasted relation to the last, temporarily fastening the marginal edges of the upper to the last by means penetrating the upper from within the shoe, placing an outsole on the lasted upper, securing the outsole and upper permanently together while on the last by a thread seam, the stitches of which pass through the parts and appear at the outer surface of the outsole and inside of the shoe and finally withdrawing the temporary fastening means to permit the shoe to be removed from the last.

8. A machine for use in the manufacture of shoes having, in combination, a last, and means cooperating with the last to work an upper into lasted position over the last and to secure an outsole permanently to the lasted upper by a thread seam, the stitches of which pass through the parts and appear at the outer surface of the outsole and inside of the shoe.

9. A machine for use in the manufacture of shoes having, in combination, a last, means cooperating with the last to work an upper into lasted position over an insole on the last and to secure an outsole to a lasted upper and insole by a thread seam, the stitches of which pass through the parts and appear on the outer surface of the outsole and the inner surface of the insole, and means for temporarily holding the insole and upper together while the outsole is being secured thereto.

10. A machine for use in the manufacture of shoes having, in combination, a hollow last, upper clamping and wiping means cooperating with the last to work a shoe upper into lasted position over an insole on the last, and sewing mechanism to secure an outsole to the lasted upper and insole on the last by a thread seam, the stitches of which pass through the parts and appear on the outer surface of the outsole and the inner surface of the insole.

11. A machine for use in the manufacture of shoes having, in combination, a hollow last, upper clamping and wiping means movable relatively to the last towards and from positions to work the upper into lasted condition over an insole on the last, sewing mechanism also movable relatively to the last towards and from a position to secure an outsole permanently to the upper and insole by a thread seam, the stitches of which pass through the parts and appear on the outer surface of the outsole and the inner surface of the insole, and fastening devices for engaging the upper and insole while held by the wiping means to temporarily hold the parts until the seam is completed.

12. A machine for use in the manufacture of

shoes having, in combination, a hollow last, upper clamping and wiping means movable relatively to the last towards and from positions to work the upper into lasted condition over an insole on the last, sewing mechanism also movable relatively to the last towards and from a position to secure an outsole to the upper and insole by a thread seam, the stitches of which pass through the parts and appear at the outer surface of the outsole and the inner surface of the insole, fastening devices for holding the upper and insole temporarily together while the wiping means is being moved away and the sewing mechanism is being moved into operating position, and a member operable to withdraw the fastening devices after the seam is completed.

13. A machine for use in the manufacture of shoes having, in combination, a hollow last, upper clamping and wiping means movable relatively to the last towards and from positions to work the upper into lasted condition over an insole on the last, sewing mechanism also movable relatively to the last towards and from a position to secure an outsole to the upper and insole by a thread seam, the stitches of which pass through the parts and appear at the outer surface of the

outsole and the inner surface of the insole, sticker points within the last, and means for projecting the sticker points through the bottom of the last to hold the upper and insole temporarily together while the wiping means is being moved away and the sewing mechanism is being moved into operating position.

14. A machine for use in the manufacture of shoes having, in combination, a last, means for permanently securing an outsole to a lasted upper retained on the last, and means extending into the bottom of the last and engaging the side edges of the outsole to bring the outsole into proper registry with the shoe bottom while securing the outsole to the upper.

15. A machine for use in the manufacture of shoes having, in combination, a last, means for permanently securing an outsole to a lasted upper retained on the last, a shaft extending into an opening within the heel seat of the last and yielding means connected to the shaft for engaging the side edges of the outsole to bring the outsole into proper registry with the shoe bottom while securing the outsole to the upper.

25 ANTHONY LABRIE.
